UNITED STATES PATENT OFFICE.

GEORGES GILES, OF FRIBOURG, SWITZERLAND.

ELECTROLYTIC LIGHTNING-ARRESTER.

1,150,590.

Specification of Letters Patent. Patented Aug. 17, 1915.

Application filed March 13, 1913. Serial No. 753,908.

To all whom it may concern:

Be it known that I, GEORGES GILES, engineer, a citizen of the United States, residing at Fribourg, Canton of Fribourg, in

the Confederation of Switzerland, have invented certain new and useful Improvements in Electrolytic Lightning-Arresters, of which the following is a specification.

The present invention relates to an electrolytic lightning arrester and the object thereof is to overcome certain disadvantages of the present lightning arresters of this kind.

A lightning arrester which consists of a simple electrolytic condenser which is connected with continuous current mains operates satisfactorily as long as the designed voltage is not exceeded, or is varied gradually, but the instrument breaks down when for instance the voltage suddenly doubles.

In alternate current work the polarity of the electrodes is reversed at the end of each period and a film is alternately formed on both the electrodes. The condenser then works like a simple resistance between the moment when the film is perforated on one electrode and the moment when it is formed on the other electrode. There is a consequent leakage of current which produces a heating of the apparatus and tends to prevent the regular formation of the film, resulting in the ultimate destruction of the condenser. In order to overcome these objections it has been proposed to connect the condenser in series with a spark-gap. The condenser being then not normally under current must be charged every day by short-circuiting the spark-gap for a required time. This operation is delicate, difficult, and uncertain.

In working out this invention it was my purpose to find an apparatus which may be connected with the mains without an intermediate spark-gap and which is operative at a voltage near the normal working voltage. This is possible only in an apparatus which permits the arrangement in a small volume of a large number of elements in series in such a manner that each element has to carry only a relatively few volts. In this manner the heating of the apparatus even in alternate current use is avoided. On the other hand an electrolytic apparatus based on the film principle is never intended for an excessive voltage and is punctured immediately, when, for instance, double the

normal voltage is applied thereto, and this is so even when it is made in such a manner that one element is designed for only 2 to 3 volts.

According to the present invention, the desired result is obtained by the employment of conducting elements or members which are in contact with one another, forming a chain the ends of which are connected with the terminals of the apparatus, these elements being placed in a liquid which forms an insulating film when the chain is submitted to a difference of potential. By increasing the number of the elements forming the chain, the tension between the neighboring elements may be reduced at will and a chain of great length and formed of a large number of elements may be placed in a small space. In order to prevent the chain-links from welding together during the passage of a current due to an excess voltage, a resistance may be connected in series with the chain.

In the accompanying drawing, Figure 1 is a side elevation of a lightning arrester illustrating a simple form of my invention. Fig. 2 is a longitudinal section of a modification thereof. Fig. 3 is a side elevation of another modification. Fig. 4 and Fig. 5 are respectively a longitudinal section and a plan view of a further modification, and Fig. 6 is a longitudinal section of a modification of the form shown in Figs. 4 and 5.

The lightning arrester represented in Fig. 1 comprises a tube *a* of insulating material, such for example as glass, which contains distilled water *b* or other material, and in which is a chain *c*, for instance, of aluminum, the links of the chain being of any desired form. If a voltage is applied to the ends of the chain, an insulating film is formed on the links which prevents the passage of current through the apparatus. In the case of a sudden excess voltage being applied the film is temporarily broken and permits a current to pass through the apparatus, momentarily, and then the film is reformed preventing a permanent short circuit through the apparatus.

In the form of the invention shown in Fig. 2 rings *d*, made for instance of aluminum, are strong on an insulating tube *e* between an end piece *f¹* and a ring *f²* made of conducting material. The end piece *f¹* is supported by a conducting shaft *g* which is placed in the tube *e*. The end of the shaft

g projects out of the upper end of the tube *e* and forms one of the terminals of the apparatus. A spring *h* extends between the ring *f* and a conducting piece *i*, forming 5 the second terminal of the apparatus and which maintains the rings *d* in contact. A lead wire *g'* may be connected to the shaft *g* by a binding nut *g''*, and a lead wire *i'* may be connected to the conducting piece *i* 10 by a binding screw *i''* or otherwise. The piece *i* is fixed in the upper portion of an insulating receptacle for containing water or other material, and closes the receptacle tightly. This form of the lightning arrester 15 works in the same manner as the form shown in Fig. 1.

In order to prevent the passage of electric currents between any of the rings *d* through the liquid an insulating tube provided with 20 holes and with an insulating cover for instance a cylindrical wick of cotton may be placed around the rings as shown by dot and dash lines in Fig. 2.

The Fig. 3 shows another form of the invention, in which the chain *l*, formed of 25 aluminum links, is placed in the jets of water of a water-jet lightning arrester of the usual kind.

The form shown in Fig. 4 and Fig. 5 comprises a body *m* of insulating material, which is placed like an ordinary insulator on a shaft *n*. *o*¹ and *o*² are two sections of a main 30 in which the apparatus is placed and which are connected together by means of an ordinary self-induction coil *p*. The body *m* forms a reservoir containing a liquid *m*¹ into which extends a cylindrical projecting portion *m*² of the cover *m*³ which is held in place on the body *m* by the screw-nut *m*⁴. On the 35 projecting portion *m*² is a helical tube *r* of insulating material. One end of the tube *r* is fixed in the cover *m*³ and contains the chain *s*. One end of this chain is secured in the conducting piece *t* which is supported by 40 the cover, and is connected, by means of the conductor *u*, to one of the sections of the main. The other end of the chain is connected to a conducting ring *v* which is arranged on the projection *m*² of the cover. 45 The liquid which is interposed between the

ring *v* and the shaft *n* through which the excess voltage passes to earth, forms a resistance which prevents the links of the chain from welding together when an excess voltage passes.

55

The Fig. 6 shows a further modification wherein the self-induction coil is made of a conductor *x* which is arranged in a groove in the outer surface of the hollow body *m*. In this modified form the chain *s* is placed 60 in a helical channel *m*¹⁰ arranged in the projecting cylindrical portion *m*¹¹ of the cover.

65

I claim as my invention:

1. An electrolytic lightning arrester comprising a receptacle, a plurality of aluminum links in contact with one another forming a chain passing through the said receptacle, and a solution also within the said receptacle, in which the links of the chain are immersed for re-forming an insulating film on the surface of the links when the same are subjected to a difference of potential.

70

2. An electrolytic lightning arrester comprising a liquid tight receptacle, a member 75 extending into the said receptacle and having a helical channel provided therein, a chain formed of aluminum links placed in the said helical channel, and an aqueous solution in the said receptacle forming a resistance in series with the said aluminum links of the chain.

70

3. An electrolytic lightning arrester comprising a liquid tight receptacle, a member 80 extending into the said receptacle and having a helical channel provided therein, a chain formed of aluminum links placed in the said helical channel, an aqueous solution in the said receptacle forming a resistance in series with the said aluminum links of the chain, and a conductor comprising a self-induction coil wound directly upon the surface 85 of the said receptacle.

90

In testimony whereof I have affixed my signature in presence of two witnesses.

GEORGES GILES.
